UNITED STATES PATENT OFFICE.

CHARLES F. IRONS, OF PROVIDENCE, RHODE ISLAND.

DESIGN FOR A BADGE.

SPECIFICATION forming part of Design No. 21,512, dated May 3, 1892.

Application filed March 26, 1892. Serial No. 426,604. Term of patent 3½ years.

To all whom it may concern:

Be it known that I, CHARLES F. IRONS, a citizen of the United States, residing at Providence, in the county of Providence, in the 5 State of Rhode Island, have invented and produced a new and original Design for a Badge, of which the following is a specification, reference being had to the accompanying drawing, which shows in front view the badge and 10 forms a part hereof.

The leading features of my design are a Maltese cross, upon which is a triple cross, and upon the latter a circular band, within 15 which circle are displayed a landscape representing the mountain of the Holy Cross and the initial "C," with a cross and crown inclosed therein, all marked and ornamented as hereinafter specified.

The base of my design is a Maltese cross. 20 A triple cross appears to rest upon the Maltese cross, and its respective long arms extend over and beyond the outer center of each arm of the Maltese cross, respectively. At the 25 ends of said principal arms of this triple cross are shown diminutive crosses, as follows: on the upper arm a small triple cross, on the left arm a double or patriarchal cross, on the right arm a Latin cross, and on the lower arm a Maltese cross. A circular band is centrally displayed, and its interior, which is the center 30 of the design, is occupied with these several particulars: at the top a scroll or floating ribbon, at the center a landscape of a mountain range, whose foremost peak has a white cross diagonally disposed, like the mountain of the 35 Holy Cross, and at the lower part the initial letter "C," within the curve of which is seen a passion cross and crown surrounded by divergent rays. The outer edge or margin of the base Maltese cross has an ornamental 40 chasing. The outer exposed margin of the large triple cross is plain, and within said margin the arms of the cross are matted or mottled.

The design for a badge, herein described and shown.

CHARLES F. IRONS.
